SUCTION CLEANER FLOOR TOOL

Frederick Riebel, Jr., Toledo, Ohio, assignor to
Air-Way Electric Appliance Corporation, To-
ledo, Ohio, a corporation of Delaware

Application April 3, 1934, Serial No. 718,828

11 Claims. (Cl. 15—155)

This invention relates to suction cleaners of the type wherein the nozzle or floor tool is resiliently mounted on rollers disposed at its ends, and has for its object to provide means whereby 5 the floor tool may be adjusted for height to any of a series of normal riding positions determined by the balance between the weight of the floor tool and the tension of the resilient portions of the mountings when flexed under said weight, 10 below any one of which positions the floor tool may be depressed under manual pressure.

Fig. 1 is a longitudinal sectional view through one end of a floor tool embodying the invention.

Fig. 2 is a plan view of the same.

Fig. 3 is a view, similar to Fig. 1, of a modification of the invention.

Fig. 4 is a rear elevation of the same.

Fig. 5 is an end view of the same.

Fig. 6 is a view of the adjusting means of Fig. 2, parts being shown in section.

Fig. 7 is a view similar to Fig. 1 of another modification of the invention.

Fig. 8 is a perspective view of a portion of a vacuum cleaner embodying the invention.

The floor tool is supported by a pair of rollers 31 one at each end of the tool. The rollers 31 are attached to mountings which in turn are attached to the floor tool. Each mounting includes a resilient portion which serves to carry the weight of the cleaner to the roller, and which allows the tool to be depressed below a normal riding position determined by the balance between the weight of the cleaner 33 and the tension on the resilient portion of the mounting.

The present invention is distinguished from other devices of this general nature, in that the roller mounting comprises simply a leaf spring, fulcrumed intermediate its ends beneath a portion of the floor tool, the roller being journalled on the outer end of the spring, and adjustment being effected by an adjusting element exerting adjustable upward pressure against the other end of said spring, and serving to vary the height of said other end relative to the floor tool.

In Fig. 1, the mounting comprises simply a leaf spring bracket 75, having a depending arm 37b on which the roller 31 is journalled. The bracket 75 is fulcrumed below a lug 76 secured to the top wall of the bracket, and its free end has an opening receiving the neck 71a of an adjusting screw 71, threaded through the top wall of the socket 36. The neck 71a has a head 71b which carries the weight of the floor tool from the screw 71 to the spring 75. The neck 71a serves

to retain the spring 75 against endwise removal from the floor tool.

Rotation of the adjusting screw 71 in one direction will draw the end of the bracket 75 closer to the top wall of the socket 36, which will elevate the bracket at the region of engagement with the fulcrum 76 and thereby lift the floor tool to a higher elevation, other conditions remaining the same. The height at which the floor tool will ride when only the weight of the cleaner 10 is imposed upon the bracket 75, may be termed the normal riding position. There will be several riding positions, one for each position of adjustment of the screw 71. Below each of these normal positions the floor tool may be depressed 15 by adding manual pressure to the weight of the floor tool. As the floor tool is thus manually depressed, the spring bracket 75 will be bowed around the fulcrum 76.

The same adjustment may be accomplished by 20 the cam adjusting element 78 of Fig. 3. The cam 78 is oscillatorily mounted in the side walls of the socket 36, projecting therethrough at one end and equipped with a lever 79 which cooperates with a keeper plate 80, a spring pressed ball 81 25 engaging detents 82 in the plate. In this form the spring 75 has at its inner end a downbent hook 84 which engages in a notch 83 in the floor tool or against the cam 78, for the purpose of preventing endwise removal of the spring. 30

In Fig. 7, instead of the fulcrum 76, the spring 75a is bent to form its own fulcrum at 75b. The operation is the same as that of the device shown in Fig. 1.

In this respect the present invention distinguishes from my prior Patents Nos. 1,899,107, 1,899,108, and 1,899,423, in which the magnitude of possible arcuate movement of the floor tool bracket is reduced as the tension on the spring is increased. In the present invention, the bracket 75 may swing the full height of the mouth of the socket 36, no matter what may be the position of adjustment of the adjusting element 71. This is accomplished by positioning the adjusting means at the inner end of the socket. 40 45

The invention also has the advantage that the possible range of depression of the floor tool below normal riding position is not varied by change of adjustment.

This application is a continuation in part of the 50 application for my above numbered patents, and of my application Serial Number 658,684, filed Feb. 27, 1933.

I claim as my invention:

1. In a suction cleaner, a floor tool having an 55

- end socket, a supporting roller, a mounting bracket for said roller comprising a leaf spring on one end of which said roller is journalled, said bracket projecting longitudinally into said socket, and 5 means for attaching its opposite end to the floor tool, for carrying the weight of the floor tool to the roller through said bracket, and for adjusting the height at which said floor tool is supported by the roller, said means being located at 10 the inner end of the socket so that the bracket may swing vertically the full height of the mouth of said socket, in any of its several positions of adjustment, under pressure applied to the floor tool.
- 15 2. In a suction cleaner, a floor tool, a supporting roller, a mounting for said roller comprising a leaf spring on one end of which the roller is journalled, a fulcrum member carried by the floor tool, engaging an intermediate region of said 20 spring from above, an adjusting element engaged between the other end of said spring and the floor tool, said element exerting upward pressure against and being operative to vary the height of said other end of the spring relative to the fulcrum and means for retaining said spring in position relative to the floor tool.
- 25 3. In a suction cleaner, a floor tool, a supporting roller, a mounting for said roller comprising a leaf spring on one end of which the roller is journalled, a fulcrum member carried by the floor tool, engaging an intermediate region of said 30 spring from above, an adjusting screw threaded into the floor tool and engaging the other end of said spring from below to vary the height of said other end relative to the fulcrum and means for retaining said spring in position relative to the floor tool.
- 35 4. In a suction cleaner, a floor tool, a supporting roller, a mounting for said roller comprising a leaf spring on one end of which the roller is journalled, a fulcrum member carried by the floor tool, engaging an intermediate region of said 40 spring from above, an adjusting screw threaded downwardly through the floor tool, its lower end formed with a head received by and engaging beneath the other end of said spring and means for retaining said spring in position relative to the floor tool.
- 45 5. In a suction cleaner, a floor tool, a supporting roller, a mounting for said roller comprising a leaf spring on one end of which the roller is journalled, a fulcrum member carried by the floor tool, engaging an intermediate region of said 50 spring from above, an adjusting cam rotatably mounted in the floor tool and engaging the other end of said spring from below and means for retaining said spring in position relative to the floor tool.
- 55 6. In a suction cleaner, a floor tool, a supporting roller, a mounting for said roller comprising a leaf spring on one end of which the roller is journalled, said spring being fulcrumed intermediate its ends beneath a portion of the floor 60 tool, an adjusting element engaged between the other end of said spring and the floor tool, said element being operative to vary the height of said other end of the spring relative to the fulcrum, the said other end being provided with a hook engaging the floor tool to prevent longitudinal retraction of the spring and means for retaining said spring in position relative to the floor tool.

other end of said spring and the floor tool, said element exerting upward pressure against and being operative to vary the height of said other end of the spring relative to the fulcrum and means for retaining said spring in position relative to the floor tool.

7. In a suction cleaner, a floor tool, a supporting roller, a mounting for said roller comprising a leaf spring on one end of which the roller is journalled, said spring being fulcrumed intermediate its ends beneath a portion of the floor tool, an adjusting screw threaded into the floor tool and engaging the other end of said spring from below to vary the height of said other end relative to the fulcrum and means for retaining said spring in position relative to the floor tool.

8. In a suction cleaner, a floor tool, a supporting roller, a mounting for said roller comprising a leaf spring on one end of which the roller is journalled, said spring being fulcrumed intermediate its ends beneath a portion of the floor tool, an adjusting screw threaded downwardly through the floor tool, its lower end formed with a head received by and engaging beneath the other end of said spring and means for retaining said spring in position relative to the floor tool.

9. In a suction cleaner, a floor tool, a supporting roller, a mounting for said roller comprising a leaf spring on one end of which the roller is journalled, said spring being fulcrumed intermediate its ends beneath a portion of the floor tool, an adjusting cam rotatably mounted in the floor tool and engaging the other end of said spring from below and means for retaining said spring in position relative to the floor tool.

10. In a suction cleaner, a floor tool, a supporting roller, a mounting for said roller comprising a leaf spring on one end of which the roller is journalled, said spring being fulcrumed intermediate its ends beneath a portion of the floor tool, an adjusting element engaged between the other end of said spring and the floor tool, said element being operative to vary the height of said other end of the spring relative to the fulcrum, the said other end being provided with a hook engaging the floor tool to prevent longitudinal retraction of the spring and means for retaining said spring in position relative to the floor tool.

11. In a suction cleaner, a floor tool, a supporting roller, a mounting for said roller comprising a leaf spring on one end of which the roller is journalled, said spring being fulcrumed intermediate its ends beneath a portion of the floor tool, an adjusting element engaged between the other end of said spring and the floor tool, said element being operative to vary the height of said other end of the spring relative to the floor tool, the said other end being provided with a hook engaging said adjusting element to prevent longitudinal retraction of the spring, and means for retaining said spring in position relative to the floor tool.
